US00D850083S

(12) **United States Design Patent** (10) **Patent No.:** **US D850,083 S**
(45) **Date of Patent:** **** Jun. 4, 2019**

(54) **FOOTWEAR SOLE**

(71) Applicant: **TBL Licensing LLC**, Stratham, NH (US)

(72) Inventors: **Kyle M. Jenkins**, Reading, MA (US); **Pierome Sar**, Stratham, NH (US); **Sam Grande**, Portsmouth, NH (US)

(73) Assignee: **TBL Licensing LLC**, Stratham, NH (US)

(**) Term: **15 Years**

(21) Appl. No.: **29/641,188**

(22) Filed: **Mar. 20, 2018**

(51) LOC (11) Cl. **02-04**

(52) U.S. Cl. **USPC D2/959; D2/947; D2/951; D2/953; D2/957; D2/960**

(58) **Field of Classification Search**

USPC **D2/902, 906, 908, 916, 918, 925, D2/946-962, 977; 36/1, 1.5, 3 B, 22 R, 36/24.5, 25 R, 28, 32 R, 34 R, 59 C, 36/67 A, 101-107, 114-116, 117.3, 117.4, 36/124-136; D12/544**
CPC **A43B 13/00; A43B 13/02; A43B 13/023; A43B 13/026; A43B 13/04; A43B 13/08; A43B 13/10; A43B 13/12; A43B 13/14; A43B 13/141; A43B 13/143; A43B 13/16; A43B 13/18; A43B 13/181; A43B 13/187; A43B 13/189; A43B 13/20; A43B 13/22; A43B 13/223; A43B 13/24; A43B 13/28; A43B 13/30; A43B 13/32; A43B 13/34; A43B 13/36**

(57) **CLAIM**

The ornamental design for a footwear sole, as shown and described.

DESCRIPTION

FIG. 1 is a perspective view of a footwear sole in accordance with an embodiment of the ornamental design;

FIG. 2 is a front elevational view of the footwear sole in accordance with the embodiment;

FIG. 3 is a back elevational view of the footwear sole in accordance with the embodiment;

FIG. 4 is a left side elevational view of the footwear sole in accordance with the embodiment;

FIG. 5 is a right side elevational view of the footwear sole in accordance with the embodiment;

FIG. 6 is a top plan view of the footwear sole in accordance with the embodiment; and,

FIG. 7 is a bottom plan view of the footwear sole in accordance with the embodiment.

Broken lines are used to show unclaimed environment only and form no part of the claimed design.

1 Claim, 7 Drawing Sheets
